UNITED STATES PATENT OFFICE.

GEORGE W. MANNING, OF CHICAGO, ILLINOIS.

BROOM-MAKING MACHINE.

1,281,804.

Specification of Letters Patent. Patented Oct. 15, 1918.

Application filed August 3, 1917. Serial No. 184,186.

To all whom it may concern:

Be it known that I, GEORGE W. MANNING, a citizen of the United States, and a resident of Chicago, in the county of Cook and 5 State of Illinois, have invented certain new and useful Improvements in Broom-Making Machines, of which the following is a specification, reference being had to the accompanying drawings.

10 My invention relates to broom making machines of the general type shown in Letters Patent granted to me on February 18, 1913, No. 1,058,192. It is one of the objects of my invention to provide in a machine of 15 this general type means for pushing or otherwise clearing the broom corn or other broom material from between the handle portions of the clamps so as to provide free and easy entrance for the handle when the 20 broom is completed. It is another object of my invention to provide means for clearing the broom material away in this manner after the clamps have been partially pressed together but before the complete pressure is 25 applied to the clamps. It is another object of my invention to provide for driving in 30 the ears at the sides of the clamps both before and after the pressing operation, the broom material being thus firmly gripped 35 between the ears and the clench pins or other devices for securing the clamps together in compressing position. It is another object of my invention to provide an improved form of supporting and spacing means 40 adapted to coöperate with the rotary table for holding the bundles of broom material in proper position for receiving the clamps. It is another object of my invention to provide means for feeding the clamps properly 45 into position in the chucks, this being preferably accomplished automatically in proper timed relation to the other operations of the machine. It is another object of my invention to provide means for applying 50 clench pins and properly fastening them in position for securing the clamps together in lieu of the rivets heretofore employed. It is another object of my invention to provide new 55 and improved means for feeding the clench pins or other fastening devices, whereby the delivery of the fastening devices is prevented when at any time a chuck passes the fastening point without a bundle of broom material in position thereon between its accompanying clamps. It is another object of my invention to provide improved means for

holding the pivotally mounted chucks yieldingly in raised position. It is another object of my invention to provide improved means for closing the pivotally mounted 60 chuck with the clamp carried thereby down upon the bundle of broom material preparatory for the compressing operation. It is still another object of my invention to improve mechanisms of this type in sundry details hereinafter pointed out. The preferred 65 means by which I have accomplished my several objects are illustrated in the drawings and are hereinafter specifically described. That which I believe to be new 70 and desire to cover by this application is set forth in the claims.

In the drawings:

Figure 1 is a top or plan view of the rotary table which serves as the carrier for 75 my improved machine, the column upon which the table is revolubly mounted being shown in cross-section;

Fig. 2 is a vertical cross-section taken substantially on line 2—2 of Fig. 1, showing the 80 means for closing the pivotally mounted chuck;

Fig. 3 is a vertical cross-section, taken substantially on line 3—3 of Fig. 1, showing the 85 means for applying pressure to the clamps with the bundle of broom material contained between them;

Fig. 4 is a vertical cross-section, taken substantially on line 4—4 of Fig. 1, showing the 90 means for driving the clench or other pins through the clamps and the interposed broom material;

Fig. 5 is a vertical cross-section through 95 two of the clamps with a bundle of broom material interposed between them, showing the clench pins being secured in position and showing the ears at the sides of the clamps being driven inward toward the clench pins;

Fig. 6 is a vertical cross-section through 100 the sliding feeding plates of the clench pin feeding device;

Fig. 7 is a vertical cross-section through 105 the clench pin driving head, showing the drivers in position for an operative stroke;

Fig. 8 is a vertical cross-section, showing 110 the means for raising the pivotally mounted chuck relative to the fixed chuck and for holding it in raised position;

Fig. 9 is a vertical cross-section, showing 115 the means for clearing the broom material from the handle portions of the clamps;

Fig. 10 is a perspective view of the punch shown in Fig. 9 for clearing the broom material from the handle portions of the clamps;

Fig. 11 is a vertical cross-section through the means for delivering the clamps from a stack into position upon the horizontally-positioned chuck;

Fig. 12 is a vertical cross-section through the means for delivering the clamps from a stack and pushing them into position upon the vertically-positioned pivotally mounted chuck; and

Fig. 13 is a view showing the arrangement of the slide plates in connection with a hopper for delivering rivets or clench pins to the clamps.

Referring to the several figures of the drawings, in which corresponding parts are indicated by the same reference characters,

20 indicates a column rising from a base 21, having a table or carrier 22 revolvably mounted thereon. The table 22 is provided with a plurality of horizontally-disposed chucks 23 each adapted to receive in position thereon a broom clamp 24, as shown at the right in Fig. 1. Pivotally mounted adjacent to each of the horizontally-disposed chucks 23 is a coöperating chuck 25 each of which 25 is adapted to have an appropriate clamp 26 delivered thereto, as is best shown in Fig. 12.

Means is provided for rotating the table 22 intermittently step by step. As each of the chucks 23 comes into the position directly at the right in Fig. 1, an operator places a bundle of broom material 27 in position upon the clamp 24 and promptly closes the chuck 25 with the clamp 26 therein down upon the bundle. This is effected preferably 35 by means of a foot lever 28 pivotally mounted upon the column 20 connected at its inner end by means of a link 29 with a bell-crank lever 30, the vertically extending arm of which is connected with a punch or ram 31 40 which is moved outward for forcing the chuck 25 down upon an appropriate downward movement of the lever 28 against the action of the spring 32. The chuck 25 is normally held in raised position by means 45 of a catch device 33 mounted upon the chuck 25 in engagement with a catch device 34 carried by the chuck 23, the catch devices 33-34 being adapted to yield sufficiently to permit of a yielding engagement and disengagement.

Means is provided for supporting the outer ends of the bundles 27 as they are placed successively in position upon the chucks 23 in the movement of the table 22. 50 This means is illustrated at one portion of the showing of Fig. 1. It will be understood that this supporting means in practice extends clear about the table 22, but is omitted for clearness of illustration. This supporting means comprises arms 35 extending

outward from the table 22 supporting an annular band 36. Arms 37 are adjustably mounted upon the band 36 and rise therefrom, having their upper ends turned so as to be embraced by sleeves 38. As will be readily understood, the arms 37 can be adjusted relative to each other so as to vary the distance between the adjacent arms, there being thus provided supporting and spacing means adjustable to meet varying conditions 75 in the size of bundles of broom material employed.

As the rotary table advances with the chuck closed down upon the bundle as shown at the right in Fig. 1, this chuck comes to the point where pressure is applied for compressing the clamps upon the bundle of broom material. Pressure is applied to the uppermost chuck 25 by means of a pressure head 39 mounted upon the lower end of a 80 ram 40 which is slidably mounted in suitable brackets 41-42 extending laterally from the column 20 (see Fig. 3). The ram 40 has pressure applied thereto by means of a collar 43 which is connected by means 85 of toggle arms 44-45 with the bracket 41. The joint of the toggle arms 44-45 is connected by a link 46 with the vertically-extending arm of a bell-crank lever 47, the other arm of which is connected by means 90 of a link 48 with any suitable power device 95 which is actuated in timed relation to the motion of the rotary table for moving the pressure head 39 downward as is desired. The link 48 is preferably actuated by a suitable cam mechanism in the manner fully illustrated in my patent above referred to. When the uppermost chucks 25 have been moved downward to the limit of their motion, they are held in compressing position 100 by means of spring latch devices 49, as is best shown in Figs. 3 and 4.

When the pressure head 39 has made a partial downward stroke, a ram 50 is moved outward through a suitable opening in the 110 side of the column 20 (see Fig. 9) for pushing the partially compressed broom material out of the handle portions of the clamps 24-26. As is best shown in Fig. 10, the ram 50 is built up of a plurality of separate parts, 115 whereby its size and shape may be regulated to suit the thickness of broom being manufactured. As is best shown in Fig. 9, the ram 50 is operated by means of a link 51 connected with one end of a bell-crank lever 120 52, the other end of which has a vertically-slidable connection with the ram 50 by means of a slide-box 53 thereon. The link 51 is adapted to be operated by any suitable power mechanism in timed relation to the action 125 of the pressure head 39, so as to have its action after the bundle of broom material is partially compressed and before the entire pressure has been applied.

Means is provided at the pressure station 130

of the machine for driving in the ears 54 carried at opposite sides of the clamps 24—26, in substantially the manner illustrated in my said patent. This means comprises rams 5 or punches 55 mounted at the sides of the pressure head 39 which are adapted to force inward the slide-blocks 56, the inner ends of which engage the ears 54, as is best shown in Fig. 5. The rams 55 in their downward movement engage also pressure blocks 57 fixed in appropriate position upon the table 22, as is best shown in Fig. 1.

When the pressure has been applied to the chucks as just described, the chucks are next moved to the riveting station of the machine. A driving head 58 is slidably mounted in a bracket 59 extending outward from the column 20 in position to permit the compressed chucks to pass under. The driving head 58 is connected by means of bolts 60 with a crosshead 61 mounted upon the lower end of a punch or ram 62 which is slidably mounted in a bracket 63 extending from the column 20. Heavy coiled springs 64 are inserted upon the bolts 60 between the crosshead 61 and the driving head 58 serving to hold the driving head yieldingly downward relative to the crosshead 61 (see Fig. 4 for this construction). The driving head 58 is provided with tubes 65 which have telescopic connection with other tubes 66 (see Fig. 7) for delivery of rivets or pins from a suitable source to the driving head 58, such tubes 65 corresponding in number and position with the number of openings through the clamps for receiving such pins for securing the clamps together about the bundle of broom material. In Fig. 7 a pin 67 is shown in position in a suitable socket 68 in the driving head 58 ready to be driven through the openings of the clamps upon the descent of the rams 69, as hereinafter described. The pins or rivets 67 are held yieldingly in position by means of slide-blocks 70 pressed yieldingly toward each other by means of suitable springs 71.

Fig. 5 illustrates two of the rams 69 driving suitable pins 67 into position, showing the lower ends of the pins being clenched or turned backward into the body of broom material by means of suitably shaped dies 72 carried by the lower chuck member 23.

As is best shown in Fig. 7, the rams 69 are fixedly mounted in the crosshead 61 and are adapted to descend therewith. The crosshead 61 and the ram 62 are adapted to be moved downward by means of toggle-arms 73—74 connected with the bracket 63 and the ram 62, respectively, the toggle joint being connected by means of a link 75 with one arm of a bell-crank lever 76, the other arm of which is connected by means of a link 77 with any suitable source of power adapted to actuate such link in proper timed relation, as is readily understood. The link 77

is also provided with a collar 78 which at substantially the end of the downward movement of the link is adapted to engage one end of a lever 79 for bringing the other end of said lever upward into contact with the dies 72 for giving said dies a slight upward movement for finishing the complete clenching of the pins 67. The crosshead 61 is also provided with rams 80 at opposite sides thereof adapted to be brought down between the stationary blocks 57 and the slide-blocks 56 for giving the ears 54 of the clamps a supplemental drive inward toward the pins 67 so as to clamp the broom material between the ears and the pins very firmly in position. Supports 81—82 for the table 22 are provided at the compressing station and the pin driving station so as to relieve the table from undue strain at these points.

The means for delivering clenched pins to the driving head 58 comprises a hopper 83 (see Fig. 13), which is pivotally mounted in suitable position and is preferably adapted to be rocked at intervals, as is described in my said patent. The pins 67 are fed to the tubes 66 by means of two slide-plates 84—85 of the type illustrated in my patent. As is best shown in Fig. 6, the slide-plates 84—85 are adapted to be moved relative to each other by means of two plungers 86—87 which work in suitable openings in said plates. The plunger 86 is connected with an arm 87^a extending from the cross-head 61, the plunger 86 being given a positive up and down movement with said crosshead. The plunger 87 in turn is connected by means of a link 88 with an arm 89 which is adapted to be swung up and down about a shaft 90 as an axis by means of an arm 91 which is adapted to be engaged by a bundle of broom material on the chuck in compressing position. When there is a broom in position in each of the chucks as it arrives at the compressing position, the plunger 87 is moved upward by the upward movement of the arm 91 actuated by the bundle of broom material. When, however, a chuck arrives at the compressing position without a bundle of broom material in position thereon, the arm 91 remains in lowered position and the upward movement of the plunger 86 accordingly has no effect upon the plates 84—85 whereby no clenched pins are delivered. It will be understood that whether or not the plunger 87 is moved upward into the position shown in Fig. 6, the plunger 86 makes its periodical upward movements regularly with the crosshead 61. In case the link 88 is moved upward after the plunger 86 has moved upward in advance thereof, the plunger 87 is prevented from moving upward by reason of the play provided by the spring 92 interposed in the connections between the link 88 and the plunger 87, 130

the spring 92 being strong enough to raise the plunger 87 when the plunger 86 is in its lowered position, but being of insufficient strength to raise the plunger 87 when the plunger 86 has risen in advance.

After the completion of the broom at the clenching station as just described, the further movement of the table serves in any suitable manner to release the chuck 25 from the latch devices 49, the chuck 25 being then raised to its open position by means of a plunger 93 carried by an arm 94 extending from the ram 62 (see Fig. 4.) As is best shown in Fig. 8, the plunger 93 engages the latch device 33 of the chuck 25 and by downward pressure thereon raises such chuck, the latch device 33 being moved by this operation into engagement with the latch device 34. Guides or guards 95-96 are provided for preventing possible misdirection of the plunger 93, and a spring 97 is also provided for assisting in the proper control of the plunger 93.

Coming now to the means for delivering the clamps to the chucks, 98 indicates a housing adapted to hold a stack of clamps 24 (see Fig. 11). 99 indicates a plunger slidably mounted upon the bracket 100 supporting the housing 98, the inner end of said plunger being opposite the lowermost one of the clamps 24 of the stack supported in said housing. The plunger 99 is provided near its outer end with a stud or roller 101 which is adapted to be engaged by a diagonally-disposed slot 102 in a block 103 which is adapted to be moved upward in suitable timed relation for causing an inward movement of the plunger 99 for pushing the lowermost clamp 24 toward the left in said Fig. 11 so as to drop into position upon the chuck 23. The block 103 is moved upward by means of a rod 104 which is given the desired movement by any suitable mechanism in the proper timed relation.

105 indicates a housing adapted to receive a stack of the clamps 26 (see Fig. 12). A plunger 106 slidably mounted upon the housing 105 has its end portion in engagement with the lowermost clamp 26 so as to be adapted to push said lowermost clamp toward the right in Fig. 12 for delivery. The plunger 106 is operated in the construction shown by means of a lever 107 (see Fig. 9) which in turn is actuated by lugs 108 carried by the ram 50. The plate 26 delivered from the bottom of the stack in the housing 105 as above described is received into a pocket formed by plates 109-110 which are spaced apart with a plate 111 between them at their lower edges, the plate 111 being of a shape to correspond to that of the clamp 26, whereby the clamp is supported evenly in position upon the plate 111 when it falls into position thereon. The

plate 110 is provided with an opening corresponding to the outline of the clamp 26 so as to permit free movement of the clamp therethrough. Springs 112 are provided in suitable position for engaging the sides of the handle portion of the clamp in position upon the plate 111. A crosshead 113 is movably mounted in suitable position relative to the housing 105, in the construction shown being supported by means of slidably mounted pins or plungers 114 which are fixedly connected with said crosshead. The plungers 114 are provided at their end portions with pins 115 which are adapted to enter suitable openings in the clamps 26 upon a suitable movement of the crosshead 113 toward the left in said Fig. 12. As will be readily understood, when the crosshead 113 is moved toward the left to bring the pins 115 into engagement with the openings 85 of the clamp 26, a further movement of the crosshead toward the left in said figure will serve to move the clamp toward the left between the springs 112, serving to carry the clamp into position upon the chuck 25. In 90 the construction shown, the crosshead 113 is given an operative movement toward the left in Fig. 12 by means of a lever 116 operated from the ram 99 and a second lever 117 connected with the lever 116 and with 95 the crosshead 113.

As is best shown in Figs. 11 and 12, both of the chucks 23 and 25 are provided with suitable pins 118 adapted to engage the edges of the clamps so as to hold the clamps 100 in suitable position thereon. A support 119 of any suitable type is provided adjacent to the chuck 25 at the point where the clamp 26 is pressed by the rods 114 into position on said chuck.

What I claim as my invention and desire to secure by Letters Patent, is:

1. In a broom making machine, the combination of a carrier adapted to carry two broom clamps into compressing position 110 with a quantity of broom material between them, means for pressing said clamps together, and means adapted to clear the broom material from certain predetermined portions of said clamps. 115

2. In a broom making machine, the combination of a carrier adapted to carry two broom clamps into compressing position with a quantity of broom material between them, means for pushing the broom material from between certain predetermined portions of said clamps, and means for pressing said clamps together about said broom material. 120

3. In a broom making machine, the combination of a carrier adapted to carry two broom clamps into compressing position with a quantity of broom material between them, means for pressing said clamps together, a ram, and means for forcing said 125 130

- ram between certain predetermined portions of said clamps for pushing the broom material therefrom.
4. In a broom making machine, the combination of a carrier adapted to carry two broom clamps into compressing position with a quantity of broom material between them, means for pressing said clamps together, a ram of adjustable size and shape to correspond to the distance between the clamps when pressure has been applied thereto, and means for forcing said ram between certain predetermined portions of said clamps for pushing the broom material therefrom.
5. In a broom making machine, the combination of a carrier adapted to carry two broom clamps into compressing position with a quantity of broom material between them, means for pressing said clamps together, a ram, means for building up the end of said ram to vary its size, and means for forcing said ram between certain predetermined portions of said clamps.
6. In a broom making machine, the combination of a carrier adapted to carry two broom clamps into compressing position with a quantity of broom material between them, means for pushing the broom material from between certain predetermined portions of said clamps, and means for pressing said clamps together both before and after said operation of pushing the broom material from the clamps.
7. In a broom making machine, the combination of a carrier adapted to carry two broom clamps into compressing position with a quantity of broom material between them, each of said clamps comprising a handle portion, means for pushing the broom material from between the handle portions of said clamps, and means for pressing said clamps firmly together about said broom material.
8. In a broom making machine, the combination of a carrier adapted to carry two broom clamps into compressing position with a quantity of broom material between them, each of said clamps comprising ears at their opposite side portions, means for pressing said clamps together about said broom material, means for securing said clamps together, and means for pressing said ears inward against the broom material after said clamps have been secured together.
9. In a broom making machine, the combination of a carrier adapted to carry two broom clamps into compressing position with a quantity of broom material between them, each of said clamps comprising ears at their opposite side portions, means for pressing said clamps together about said broom material, means for pressing said ears inward against the broom material after the clamps have been pressed together,
- means for securing said clamps together after said ears have been pressed inward, and other means for pressing said ears inward for gripping the broom material between the ears and the clamp securing means.
10. In a broom making machine, the combination of a rotary table, means for holding a plurality of clamps in spaced relation about said rotary table, and supporting means extending outward beyond the edge of the table for supporting and spacing bundles of broom material to be placed in position on the clamps on said table, said supporting means being adjustable circumferentially for accommodating bundles of broom material of different sizes.
11. In a broom making machine, the combination of a rotary table, means for holding a plurality of clamps in spaced relation about said rotary table, an annular band extending about said table in spaced relation thereto for supporting bundles of broom material to be placed in position on said clamps, arms rising from said band and adjustable circumferentially about said table for indicating the position of said bundles, and adjustable means joining the upper ends of said arms between the spaces about the table at which the bundles of broom material are to be placed.
12. In a broom making machine, the combination of a movable carrier, a pivotally mounted chuck on said carrier adapted to receive a clamp into position thereon, means for delivering a clamp opposite said chuck, means for pushing said clamp horizontally into position upon said chuck while in a raised vertical position, and means carried by the chuck adapted to hold the clamp yieldingly in position thereon.
13. In a broom making machine, the combination of a movable carrier, a pivotally mounted chuck on said carrier adapted to receive a clamp into position thereon, a pocket opposite which said chucks pass successively and by which the chucks are adapted to be held successively in vertical position, means for delivering a clamp into said pocket, and horizontally-acting means for pushing said clamp from said pocket snugly into position upon said chuck.
14. In a broom making machine, the combination of a movable carrier, a pivotally mounted chuck on said carrier adapted to receive a clamp into position thereon, a pocket opposite which said chucks pass successively, means for delivering a clamp into said pocket, springs for holding said clamp in proper position in said pocket, and means for pushing said clamp from said pocket between said springs into position upon said chuck.
15. In a broom making machine, the combination of a movable carrier, a pivotally

- mounted chuck on said carrier adapted to receive a clamp into position thereon, a pocket opposite which said chucks pass successively, means for delivering a clamp into 5 said pocket, and a plunger provided with pins on its end portion adapted to engage suitable openings in said clamp and to push the clamp snugly into position upon said chuck.
- 10 16. In a broom making machine, the combination of a movable carrier, a plurality of chucks adapted to receive clamps into a position thereon, pins on said chucks for holding said clamps in position thereon, and 15 means for delivering clamps to said chucks successively as the carrier moves.
17. In a broom making machine, the combination of a movable carrier adapted to carry two broom clamps into compressing 20 position with a quantity of broom material between them, means for pressing said clamps together, means for delivering clenched pins into appropriate position relative to suitable openings through said clamps, and 25 means for driving said clenched pins through said clamps and for turning their end portions for holding the clamps together.
18. In a broom making machine, the combination of a movable carrier adapted to carry two broom clamps into compressing 30 position with a quantity of broom material between them, means for pressing said clamps together, a driving head adapted to be pressed down above the uppermost clamp, 35 means for delivering clenched pins to said driving head, and means for driving said clenched pins through suitable openings in said clamps.
19. In a broom making machine, the combination of a movable carrier adapted to carry two broom clamps into compressing 40 position with a quantity of broom material between them, means for pressing said clamps together, a driving head into position 45 under which the clamps and the interposed bundle of broom material are carried in the movement of the carrier, means for delivering clenched pins to said driving head, means for driving said clenched pins through 50 said openings in said clamps, and means for moving said driving head downward relative to the uppermost clamp at the commencement of the pin clenching operation.
20. In a broom making machine, the combination of a movable carrier adapted to carry two broom clamps into compressing 55 position with a quantity of broom material between them, means for pressing said clamps together, a driving head into position 60 under which the clamps and the interposed bundle of broom material are carried in the movement of the carrier, means for delivering clenched pins to said driving head, means for driving said clenched pins through 65 suitable openings in said clamps, and yield-
- ing means actuated by said pin driving means for moving said head downward relative to the uppermost clamp upon the pin clenching operation.
21. In a broom making machine, the combination of a movable carrier adapted to carry two broom clamps into compressing 70 position with a quantity of broom material between them, means for pressing said clamps together, a driving head into position under which the clamps and the interposed bundle of broom material are carried in the movement of the carrier, means for delivering clenched pins to said driving head, driving rods in vertical position having 75 their lower end portions in suitable sockets in said driving head, and means for moving said driving rods forcibly downward for driving the clenched pins through suitable 80 openings in said clamps. 85
22. In a broom making machine, the combination of a movable carrier adapted to carry two broom clamps into compressing position with a quantity of broom material between them, means for pressing said 90 clamps together, a driving head into position under which the clamps and the interposed bundle of broom material are carried in the movement of the carrier, means for delivering clenched pins to said driving 95 head, means for driving said clenched pins through suitable openings in said clamps, and suitable dies in position below the lowermost clamp adapted to receive the ends of 100 said clenched pins and direct them upward again into the broom material between the clamps.
23. In a broom making machine, the combination of a movable carrier adapted to carry two broom clamps into compressing 105 position with a quantity of broom material between them, means for pressing said clamps together, means for delivering clenched pins into appropriate position relative to suitable openings through said clamps, means 110 for driving said clenched pins through said clamps and the broom material interposed therebetween, dies below the lowermost clamp adapted to receive the ends of said 115 clenched pins, and means for driving said dies upward slightly at the end of the clenching operation.
24. In a broom making machine, the combination of a movable carrier adapted to carry two broom clamps into compressing 120 position with a quantity of broom material between them, means for pressing said clamps together, means for delivering clenched pins into appropriate position relative to suitable openings through said 125 clamps, means for driving said clenched pins through said clamps and the broom material interposed therebetween, dies below the lowermost clamp adapted to receive the ends of 130 said clenched pins, and a lever actuated by

said driving means at substantially the end of the clenching operation adapted to apply an upward pressure on said dies.

25. In a broom making machine, the combination of a carrier, a plurality of chucks fixed in spaced relation about said carrier, a plurality of pivotally mounted chucks in position to coöperate with said first-named chucks respectively, and inter-engaging 10 spring catch devices on said chucks respectively adapted to hold the pivotally mounted chucks yieldingly in raised position relative to said first-named chucks.

26. In a broom making machine, the combination of a carrier, a plurality of chucks fixed in spaced relation about said carrier, a plurality of pivotally mounted chucks in position to coöperate with said first-named chucks respectively, catch devices on said 15 first-named chucks, and other catch devices on said second-named chucks adapted to have yielding engagement with said first-named catch devices upon the raising of the pivotally mounted chucks for holding the 20 pivotally mounted chucks in raised position.

25 27. In a broom making machine, the combination of a carrier, a plurality of chucks fixed in spaced relation about said carrier, a plurality of pivotally mounted chucks in position to coöperate with said first-named chucks respectively, and foot lever means for closing the pivotally mounted chucks successively upon their fixed chucks at a 30 predetermined point in the movement of the 35 chucks with the carrier.

28. In a broom making machine, the combination of a movable carrier, a plurality of pairs of chucks spaced about said carrier each adapted to receive between them a pair 40 of clamps with an interposed bundle of broom material, slideways for carrying pins into position adjacent to each pair of clamps at a predetermined point in their movement with the carrier, means for driving said pins 45 through suitable openings in said clamps for securing the clamps together about the broom material, means for delivering pins to said slideways, a pair of plungers by an upward stroke of either of which said pin-delivering means is operated for delivering pins to said slideways when the other of the 50 plungers is already standing in its uppermost position, and yielding means interposed in the connections for one of said 55 plungers adapted to yield for preventing the operation of said pin delivering means when the other plunger is moved upward in advance.

29. In a broom making machine, the combination of a movable carrier, a plurality of pairs of chucks spaced about said carrier each adapted to receive between them a pair 60 of clamps with an interposed bundle of broom material, slideways for carrying pins into position adjacent to each pair of clamps at a predetermined point in their movement with the carrier, means for driving said pins 65 through suitable openings in said clamps for securing the clamps together about the broom material, means for delivering pins to said slideways, a pair of plungers by an upward stroke of either of which said pin-delivering means is operated for delivering pins to said slideways when the other of the 70 plungers is already standing in its uppermost position, connections between one plunger and the means for driving the previously delivered pins for moving said plunger positively upward, and yielding means interposed in the connections for the other plunger adapted to yield for preventing the operation of said pin delivering 75 means when the one plunger is moved upward in advance.

30. In a broom making machine, the combination of a movable carrier, a plurality of pairs of chucks spaced about said carrier 85 each adapted to receive between them a pair of clamps with an interposed bundle of broom material, slideways for carrying pins into position adjacent to each pair of clamps at a predetermined point in their movement 90 with the carrier, means for driving said pins through suitable openings in said clamps for securing the clamps together about the broom material, means for delivering pins to said slideways, a pair of plungers by an 95 upward stroke of either of which said pin-delivering means is operated for delivering pins to said slideways when the other of the plungers is already standing in its uppermost position, connections between one plunger and the means for driving the previously delivered pins for moving said plunger positively upward, a pivotally mounted arm adapted to be moved upward by the broom material upon one of said 100 chucks, and yielding connections between said arm and the other plunger adapted to cause said plunger to rise upon the upward movement of the arm in case the one plunger is in its lowered position but adapted to 105 yield to prevent the upward movement of said other plunger in case the one plunger is moved upward in advance.

GEORGE W. MANNING.
